FILING TRAY

Rodney J. Wood, incompetent, Dayton, Ohio, by
 Robert H. Wood, guardian, Dayton, Ohio, assignor to Remington Rand Inc., Buffalo, N. Y.

Application November 15, 1932, Serial No. 642,747

11 Claims. (Cl. 129—16)

This invention relates to filing trays and more particularly to portable trays or cases for account cards.

At the present time it is customary in book-keeping systems in offices to employ large numbers of loose cards or sheets and it is desirable that these may be conveniently handled, either in movement between different departments, from temporary to permanent files, or for and during inspection or examination of an individual card or sheet.

The present invention provides a portable card tray, adapted for such uses, wherein a number of cards or sheets may be supported and contained, being held either in upright position and retained in place by a cover member, or disposed in an inclined position, in which they may be readily inspected or handled. It comprises a base, opposite side members hingedly connected to the base and a removable false bottom or card-supporting plate disposed over the base which serves to prevent removal of the side members and also serves to conceal from view the supported ends of extensible wire bails mounted upon the base, which function to support the hinged side members in inclined position. The device is of simple construction so that there is virtually no possibility of it getting out of working order, and its construction of light sheet metal insures easy portability.

These and other objects and advantages will be apparent from the following description of a typical device embodying the principles of the invention, reference being made to the accompanying drawings, wherein:—

Fig. 1 is a perspective view of the tray in closed position, in which cards are supported in upright position and held against removal.

Fig. 2 is a vertical cross-sectional view showing the device in the closed position depicted in Fig. 1.

Fig. 3 is a vertical cross-sectional view taken at right-angles to Fig. 2, and illustrating the tray in open position, in which the cards are supported in inclined position.

Fig. 4 is an enlarged perspective view of the base member, the false bottom being indicated in broken lines in disassembled relation.

Fig. 5 is an enlarged fragmentary plan view with parts broken away, showing the releasable hinge connection between the base and false bottoms and a side member.

As shown in Fig. 1, the tray comprises a base member 10, having upwardly extending end flanges 11 and side flanges 12, and opposite side

members 13 and 14. The side member 13 has a top member 15 hinged at 16 to its upper edge, the member 15 being provided with a handle 17 by which the device may be carried. Interfitting rolled portions are provided along the adjacent edges of side member 14 and top member 15, through which a removable pin 18 may be passed to lock the base, top and side parts together in a closed rectangular configuration for retaining cards in the tray. The side members are provided at their bottom edges with inturned tongues 19, having enlarged heads 21, the tongues extending through elongated slots 22 in the flanges 12. A false bottom or card-supporting member 23 having depending flanges 24 is removably held by frictional engagement in the base member 10, the depending flanges 24 lying between and in contact with the upstanding base flanges 12. The flanges 24 have notches 25 in alignment with the slots 22 and overlying the tongues 19, the notches being of less width than the tongue heads 21, thereby locking the tongues to the base member 10 and false bottom 23. It will be seen that the edges of the slots 22 will prevent extended vertical movement of the tongues while the edges of the notches 25 will prevent horizontal movement by engaging the tongue heads 21. Sufficient play or clearance is allowed between the parts however that the connection may serve as a hinge about which the side members 13 and 14 may pivot from the closed position shown in Fig. 1 and in dotted lines in Fig. 3, to the open or inclined position shown in full lines in Fig. 3.

Substantially triangular flanges 27 overlying the base flanges 11 are provided on the vertical edges of the side members 13 and 14, the upper or base edges of the triangular flanges being retained by depending clips 28 formed on the upper edges of flanges 11. The overlapping relationship of the flanges 11 and 27 at all times during movement of the members 13 and 14 as between the full and dotted line positions of Fig. 3 results in the tray being completely closed at its bottom at all times, thereby eliminating the possibility of cards or papers contained therein slipping out between the sides and ends or having their edges mutilated by slipping partially out while or before the device is in closing movement.

Wire bails are provided to support the hinged sides 13 and 14 when they are in open or inclined position. These bails 30 and 31 comprise substantially inverted U-shaped portions disposed vertically and horizontal portions 32 and 33 re-

- spectively extending horizontally from the legs of the U-shaped portions and perpendicularly to the plane of the U-shaped portions. These horizontal portions which have enlarged ends 5 34 are slidably mounted on the base member 10, below the card-supporting member 23, the parts 32 being staggered relative to parts 33 as shown in Fig. 2. Strip members 35 and 36 substantially of the form of angle bars are secured to the 10 base 10 to provide tracks or guideways for members 30 and 31. The outer members 35, as shown in Fig. 4, extend entirely across member 10 and have portions of their upper flanges bent down horizontally thus forming shoulders 37 while the 15 inner members 36 extend only approximately half the width of base 10, and have shoulders 38 formed by cutting away the inner ends of upper horizontal flanges of the members 36. Angular slots 40 are provided in the base flanges 12, those 20 on one side of the base having their vertical portions juxtaposed and their horizontal portions extending away from each other and in alignment with the guideways formed by a member 35 and the base and by a member 36 25 and the base 10. The flanges 24 of the card-supporting member or false bottom are cut away at 41 adjacent to the slots 40 so as not to interfere with members 32 and 33 extending through the slots.
- 30 In assembling the device the side members 13 and 14 are first hinged to the base member by inserting the tongues 19 through the slots 22. This connection is completed by inserting the false bottom 23 so that the edges defining the 35 notches 25 engage between the base flanges 12 and the enlarged tongue heads 21. The bails 30 and 31 may next be inserted in their respective guideways by first compressing them and inserting the enlarged ends 34 through the large 40 portions of the key hole slots. Upon inward movement of the bails, the enlarged ends 34 will spring outwardly beyond the ends of the shoulders 37, 38. In using the tray, cards or papers may be inserted with their ends brought to 45 rest on the false bottom 10, the pin 18 being removed and the top 15 being swung back about its axis 16 for this purpose. When it is desired to inspect or examine the cards, the bails may be pulled outwardly until the enlarged ends 34 50 abut the ends of the shoulders 37, 38, which is the full line position of Fig. 3, and the sides 13 and 14 may be swung outwardly to rest upon the bails. When it is desirable to move the cards to another place, the sides may be brought to the 55 closed position shown in dotted lines in Fig. 3 and the bails moved inwardly against the tray sides. The cover 15 may then be swung to closed position and the pin 18 reinserted.
- 60 It will be understood that the specific device described may be modified as to various details, and it is intended that the invention should be commensurate in scope with the following claims.
- What is claimed is:
1. In a card tray, a base having an upstanding flange provided with a slot, a side member having a tongue extending through said slot, said tongue having an enlarged head, and a supporting member having a depending flange spacing said tongue head and said upstanding flange and retaining said tongue in said slot.
  2. In a card tray, a base member and a card supporting member parallel to and spaced from said base, one of said members having a depending flange and the other of said members an upstanding flange, one of said flanges spacing
- said base and supporting members, one of said flanges having a slot and the other of said members having a notch in alignment with said slot, and a side member having a tongue provided with an enlarged head extending through said slot and notch, the latter being of less width than said slot and enlarged head, whereby said tongue is retained in said slot until said member having the notch is removed.
3. In a card tray, a base member removably carried thereby and a card supporting member, one of said members having a slot, a side member having an interengaging tongue extending freely through said slot, and means on the other of said first members releasably engaging said interengaging tongue, to prevent said tongue from being removed from said slot until said other member is removed.
4. In a card tray, a base member having an elongated slot, a side member having a tongue extending freely through said slot and adapted for pivotal movement relative to said base member, and a card supporting member removably supported by said base member having means coacting with said slot and interengaging with said tongue to prevent removal of said tongue from said slot.
5. In a card tray, a base having apertured upstanding flanges, a card supporting member having apertured depending flanges spacing said member from the base, side members hinged to said first-named members, the hinge means comprising tongues extending from said side members through the apertured portions of said flanges of said base and card supporting members and interlocked therewith, bail members, for supporting said side members, having end portions extending through apertured portions of said flanges of the base and card supporting members and slideable into the space therebetween, and a top member hingedly connected to one of said side members and having means capable of being releasably interlocked with the other of said side members.
6. In a card tray, a base having a flange provided with slots, guideways on said base having shoulders, a bail member having portions extending through said slots and in said guideways, said portions having enlarged ends for abutment with said shoulders to limit the outward movement of said bail, and a side member hingedly connected to said base and adapted to be supported by said bail.
7. In a card tray, flanged base members forming opposed guideways on said base, said guideways having shoulders formed by the inner ends thereof, the flange of said base having angular slots, horizontal portions of said slots being in alignment with said guideways, vertical portions of said slots being arranged at the inner ends of said horizontal portions, and a bail having portions extending through said slots and into slideable engagement with said guideways, the ends of said portions being enlarged for abutment with the shoulders formed by the inner ends of said guideways, said bail being removable from said base by pressing said portions together bringing said enlarged ends in alignment with the vertical portions of said slots and inwardly of said guideways.
8. In a card tray, a base member, side members pivotally secured to said base member, and supporting members for said side members having portions slidably mounted in said base member and other portions extending upwardly along the

- outside of said side members adapted to occupy inner and outer-positions with respect to said base and to support said side members in substantially vertical or inclined positions relative to said base member.
5. In a card tray, a base member, side members, a card supporting member removably mounted in said base member, said side members, base member and card supporting member having cooperating parts detachably and pivotally connecting said side members to said base member, and means having a portion slidable in said base member for supporting said side members in vertical or inclined positions.

10. In a card tray, a base member, side members, and a card supporting member carried by said base member, said base and card supporting members having cooperating parts pivotally connecting said side members to said base member.
11. In a card tray, a base member, side members hinged to said base member, and means slidably associated with said base member and having portions disposed outwardly of said side members for supporting said side members in inclined position relative to said base member.
